(57) **CLAIM**

The ornamental design for a pet feeder and water dispenser set as shown and described.

DESCRIPTION

FIG. 1 is a front, right, and top perspective view of a pet feeder and water dispenser set, showing my new design; FIG. 2 is a front, right, and top perspective view of the water dispenser of the pet feeder and water dispenser set;

FIG. 3 is a rear, left, and bottom perspective view of the water dispenser of the pet feeder and water dispenser set; FIG. 4 is a front elevation view of FIG. 2;

FIG. 5 is a rear elevation view of FIG. 2;

FIG. 6 is a left view of FIG. 2;

FIG. 7 is a right view of FIG. 2;

FIG. 8 is a top plan view of FIG. 2;

FIG. 9 is a bottom plan view of FIG. 2;

FIG. 10 is a front, right, and top perspective view of the feeder of the pet feeder and water dispenser set;

FIG. 11 is a rear, left, and bottom perspective view of the feeder of the pet feeder and water dispenser set;

FIG. 12 is a front elevation view of FIG. 10;

FIG. 13 is a rear elevation view of FIG. 10;

FIG. 14 is a left view of FIG. 10;

FIG. 15 is a right view of FIG. 10;

FIG. 16 is a top plan view of FIG. 10; and,

FIG. 17 is a bottom plan view of FIG. 10.

The broken lines depict portions of the pet feeder and water dispenser set in which the design is embodied that form no part of the claimed design.
